UNITED STATES PATENT OFFICE.

CHARLES H. HIGBEE, OF NEW YORK, N. Y., ASSIGNOR TO ANDREW J. DAVIES, OF SAME PLACE.

LAMP.

SPECIFICATION forming part of Letters Patent No. 333,520, dated January 5, 1886.

Application filed April 4, 1885. Serial No. 161,227. (No model.)

To all whom it may concern:

Be it known that I, CHARLES H. HIGBEE, a citizen of the United States, residing in the city, county, and State of New York, have invented certain new and useful Improvements in Lamps, of which the following is a specification.

My invention relates to that class of burners in which annular wicks are used, and has for its object to facilitate the insertion of the said wicks into the narrow annular chambers intended for their reception in the lamps to which they are applied and to prevent them from becoming jammed in said chambers, and these objects I effect by means of guards of thin metal, paper, or other thin flexible material applied so as to prevent the fraying of the strands, as fully set forth hereinafter.

In the drawings, Figure 1 is a sectional elevation showing the mode heretofore employed for preventing the spreading or fraying of an annular lamp-wick. Fig. 2 is a section illustrating my improvement. Fig. 3 is a view showing one form of guard. Fig. 3½ is a view showing another form of guard. Fig. 4 is a view showing the guard applied directly to the wick. Figs. 5 and 6 are views showing modifications. Fig. 7 is a plan of Fig. 6; Fig. 8, a sectional elevation of a lamp-burner, showing my improvements.

In that class of lamps in which annular wicks have been employed it has been common to inclose or surround the wick for a greater or less portion of its length in a metallic casing, A, which facilitates the elevating of the wick D by the usual elevating appliances, and in order to introduce the wick with facility into the annular opening in the lamp intended for its reception a short inner ring or tube, B, has been inserted within the wick and held in place by lugs, projections, or indentations, the only object of the said tube being to prevent the fraying or spreading of the wick at the lower end, which would interfere with its insertion into the narrow opening, or cause it to stick or jam therein, by the rolling or folding back of the wick on itself. The necessity of inserting the ring B calls for a disagreeable manipulation of the wick, and it is sometimes difficult to apply. To avoid the necessity of using the said ring, I extend a

guard around the lower end of the wick and upward in such manner as to facilitate the insertion of the end of the wick into its opening, and at the same time generally prevent the strands from being extended or folded or rolled back on the body of the wick.

A guard adapted to accomplish the result desired may be made in different ways; but I prefer to form it of thin flexible material, which may be readily applied and secured to the exterior or interior of the wick, and with fingers which may be bent around the lower edge of the wick and upward to the other side. Thus the guard may consist of a strip of paper, C, cut to form a series of V-shaped fingers, f, and gummed at its upper edge, so that it may be pasted to the exterior of the wick, as shown in Fig. 2, and the fingers may then be bent under and into the wick D, thereby covering the lower end and confining the strands so that they will not spread in the act of inserting the wick.

The guard instead of consisting of a strip of paper may consist of a paper disk, slit, as shown in Fig. 5, so as to permit it to be folded under the edge and to both sides of the wick. In some instances the guard may be formed of a series of thin metal plates or fingers, f, of lead or other material, soldered to the exterior of a ring, A', as shown in Fig. 6, and capable of being bent beneath and within the wick.

Annular wicks as generally used in connection with Argand lamps are carried by the feed tubes A, Fig. 8, which are raised and lowered by a suitable lifting-wheel, J. In this class of lamps I sometimes used a fixed feeding-wick, W, surrounding the air-tube E, and extending into or supplied from the reservoir, 90 the guard C in such case preventing the wick strands from spreading as the wick is raised and lowered and jamming the wick in the wick-receptacle.

To prevent the upper strands of the fixed wick from spreading when the movable wick is introduced, I paste a strip, u, of paper or other flexible material over the end of the wick D and against the side of the air-tube E, which serves as a guard to effect the desired purpose, 100 and also aids the securing the fixed wick in place.

I do not claim in this application any features aimed in a separate application, Serial No. 31,229.

I am aware that it has been proposed to apply paper to a lamp-wick, so as to form a stiff ring or finger projecting beyond the end of the wick and facilitating its insertion into the wick-receptacle, and I do not claim, broadly, applying a stiffener of paper to the end of a wick. My invention is distinguished from the use of such finger by the fact that I use a thin flexible sheet, folded beneath and across the lower end or edge of the wick, so as in no way to extend the latter, the extension being objectionable when an annular wick is used, because it interferes with the carrying of the latter as far down as is desirable into the wick-receptacle.

Without limiting myself to any specific form or arrangement or application of guard, I claim—

1. The combination, with an annular wick, of a guard consisting of thin flexible material folded beneath and across the lower edge of the wick and upward on both sides, substantially as set forth.

2. The combination, with a wick, of a guard consisting of a strip or sheet of thin flexible material around the wick, and provided with fingers extending beneath the wick and upward, the body of the sheet being on one side and the fingers on the other, substantially as specified.

3. The combination, with a lamp-burner provided with a receptacle for an annular wick, of a wick-feeding tube and elevating device, an annular wick carried thereby, and a guard, *u*, crossing the lower edge of the wick and extending upward on both sides, substantially as described.

4. The combination, with a burner provided with an annular wick-chamber and a movable annular wick, of a fixed wick and a guard-strip, *u*, substantially as described.

In testimony whereof I have signed my name to this specification in the presence of two subscribing witnesses.

CHARLES H. HIGBEE.
